E. GROSSE

PLATEN PRESS

Filed Nov. 27, 1922

FIG. 1.

Fig. 2.

Inventor:
John Grosse
by
James Schaefer

UNITED STATES PATENT OFFICE.

EDUARD GROSSE, OF WACHWITZ, NEAR DRESDEN, GERMANY.

PLATEN PRESS.

Application filed November 27, 1922. Serial No. 603,717.

To all whom it may concern:

Be it known that I, EDUARD GROSSE, a citizen of Germany, residing at Wachwitz, near Dresden, Grundstrasse 8, Germany, 5 have invented certain new and useful Improvements in Platen Presses, of which the following is a specification.

The present invention relates to inking and sheet delivery devices which, by means 10 of the same conveying medium, are together guided around the middle part of the platen press serving as type bed. The novelty of the present invention consists in driving the inking rollers and delivery device by means 15 of wheels attached to the middle part of the press with connecting rods at right angles. The new movers for the grippers taking the sheets off the platen and conveying them to the table are curves of a peculiar 20 shape which cause the rotation of the grippers.

The advantages of the newly invented conveying and moving medium are clearly set forth in the following specifications. 25 The superiority of the wheels attached to the middle part of the press with connecting rods at right angles lies in their considerably simplified construction, while the curves causing the motion of the grippers 30 are distinguished by great safety in operation which is maintained even during highest speed, owing to the positive guiding of the grippers.

One form of the invention is illustrated in 35 the drawings in which Fig. 1 is a platen press with curved guide of gripper running around the connecting link and with toothed wheel attached to the middle part with connecting rods at right angles shown from the 40 side, and Fig. 2 is a sectional view of the bearing of the toothed wheel and connecting rods seen from the top.

The common driver for inking roller and gripper carrier is in this case a toothed 45 wheel which catches and carries along the connecting rods and is pivoted to the hub-like side part of the middle body of the press which has been shaped to form points of support for it.

50 The new features in this construction are not only the guiding of the gripper carriers but also the guiding of the inking rollers. In the older types of platen presses of this kind the inking rollers are conveyed by 55 means of roller supports fastened to the

crank shaft of the machine and turning with it. The inking rollers are directly placed in slit bearings of the roller supports or are arranged in movable bearings and travel without further guidance exclusively in runner 60 rails. This demands the arrangement of two roller supports each of which is fastened to one side of the machine on the crank shaft. As both roller supports circle with the crank shaft around the middle part of 65 the press and require a free passage between the latter and the outer frame, they completely separate the middle part from the outer frame and the middle part can only be suspended from the crank shaft in the outer 70 frame. A middle part suspended in this manner from the crank shaft naturally offers not sufficient resistance for the pressure of the platen.

These drawbacks have been overcome by 75 the present invention in the most simple manner by placing the inking rollers not directly in the roller supports but in special roller carriages which are guided by means of rolls in deep grooves running around the 80 middle part and which are moved by special connecting rods. The rigidly connected roller carriages travel with the inking rollers easily in the grooves around the middle part and the only purpose of the connecting 85 rods is to push or pull the carriage.

The connecting rods are not like the roller supports directly fastened to the crank shaft of the machine but are rotatably attached to the side ends, connected 90 with the outer frame, of the middle part serving as crank shaft bearing; attached with them is a toothed wheel which facilitates the circular motion. For this purpose the ends of the crank shaft bearing 95 are shaped as round hubs which in turn serve as points of support for the toothed wheel with connecting rod attached to them. As this arrangement places the toothed wheel with the connecting rod in the middle 100 part of the press, the latter does not form an obstacle for rotation and the connecting rods with the roller carriage attached can be guided completely around the middle part connected with the outer frame 105 without meeting any resistance.

The placing of the inking rollers in independent roller carriages forming an integral whole permits the moving of the roller carriages by means of only one connecting rod 110

which requires only a one-sided drive. This connecting rod with toothed wheel is placed on the hub-like end of the middle part towards the driving side of the machine 5 and the connecting rod is formed in such a way that it extends at right angles across the cross side of the machine. To this part of the connecting rod which is parallel to the inking rollers the roller carriage can 10 be attached either by means of slit bearings or flexible rods to both sides or connection can be made amidst the width of the roller carriage which requires as connecting part on both sides of the roller carriage a connecting rod. The gripper carriage can be 15 connected with the inking roller carriage by means of rods or pulled by a special connecting rod.

The above arrangement, providing for 20 only one connecting rod on the driving side of the machine, simplifies considerably the whole construction as only a one-sided drive is needed. It furthermore has the added 25 advantage which is very important that the middle part can be rigidly connected to the side frame in a manner permitting resistance. As the connecting rod is arranged at one side of the machine only, there is only 30 on this side free passage for the travel of the connecting rod required. On the other side is no free passage needed and the middle part can on that side be fastened to the side frame with its full surface whereby a 35 good and substantial connection can be established.

As shown in Figs. 1 and 2 G is the machine frame and B the middle body of the press on both sides of which the walls y have been provided. These contain one milled 40 groove h each in which the roller carriage W is guided by means of rolls g. The walls y have the form of circles which are flattened on the side opposite the platen T. Z is the main shaft in the machine frame. The 45 groove h, corresponding to the shape of the walls y, forms a circle measured from the centre of the main shaft Z and this circle shows a flattening at the point where the form D is located. The inking roller carriage W is guided in this groove h by means of connecting rod e and a gearing and moves in this groove on rolls.

The connecting rods e, as described below, rotate around a hub-like widening B' 55 of the centre body B and describe with their outer ends, as seen from the centre of the shaft Z, a circle and guide the roller carriage W with the inking rollers f in a uniform distance to the form D where the 60 roller carriage leaves its orbit and enters the plane to approach the centre Z. In order to prevent the roller carriage in this deviation from its orbit to find resistance in the connecting rods e, the latter have 65 been provided with the slit guide e' in

which the roller carriage guided therein can move up and down and also towards the inside.

The circuit travelled by the connecting rods e at each impression made by the 70 machine requires a free track, unimpeded by any machine parts, while the middle part B around which the connecting rods move must be firmly connected with the outer frame G. If the connecting rods were directly placed on the crank shaft Z, it would not be possible to connect the middle part B firmly to the outer frame G, because in that case the middle part would be suspended from the crank shaft Z passing 75 through it and be turning about the latter without any firm hold.

This difficulty has been removed by placing the connecting rods e not directly on the crank shaft Z but indirectly together 80 with a driving toothed wheel on a hub-like enlargement B' of the middle part B.

The middle part B consists of a type bed to one side of which the form D is attached while the other side forms the bearing for 85 the crank shaft Z. The crank shaft Z runs through the whole machine from one side to the other, through the middle part B as well as through the outer frame G (Figs. 1 and 2). On each side of the crank shaft Z 90 a toothed wheel a has been provided to which, by means of crank plates and cranks K, are linked the connecting rods which move the platen T. The pressure of the platen is chiefly borne by the middle part B, 95 and the side walls G serve only as support for the latter. The middle part must therefore be exceptionally strong as it is intended to stand the pressure weighing down upon the crank shaft Z and prevent any bending 100 of the shaft. For this purpose the crank shaft Z is strongly placed in side and middle bearings. The side bearings extend to the toothed wheel a and the crank plate and project through the walls of the frame G 105 (Fig. 2).

To permit free passage of the connecting rods around the middle part of the press a toothed wheel c has been put on the round crank shaft bearing B' of the middle part, 110 and this toothed wheel turns on the bearings B' as on a shaft. The crank shaft bearing B' has here again been formed as a hub-like shaft for the toothed wheel c on it. Figs. 1 and 2 give a sectional view of this arrangement. The crank shaft Z rests rotatably in the hub-like end parts B' of the middle part B. Part B' is round shaped and serves as bearing for the toothed wheel c on top of it 115 and the connecting rod e. The extreme end of the middle part B' has the shape of a jack B² which is firmly screwed together with the frame G. The middle part B is thus at its extreme part B² firmly attached to the frame while the toothed wheel c with 120

connecting rod *e* revolves independently from the crank shaft. To enable the toothed wheel *c* to be placed on the hub *B'* it is made in two sections. These two halves are 5 put on the hub *B'* and then screwed together.

The crank shaft is driven by the toothed wheel *a* (Fig. 2) keyed on to it which in turn is driven by the driving wheel *b* on the 10 shaft of the flywheel *S*. The flywheel shaft extends through the wall of the frame *G* and carries at its end the driving wheel *d* which turns the large toothed wheel *c* attached to the middle part hub *B'* (Figs. 1 15 and 2). Instead of the toothed wheels *c* and *d* other driving means of equal value may be used, as for instance chain wheels, etc.

To the toothed wheel *c* have been fastened 20 the connecting rods *e* which guide the inking roller carriage *W* around the middle part. The driving wheels *b*, *d* and the toothed wheels *a*, *c* are equally large each 25 and their revolution is therefore equal. In the same time in which the toothed wheel *a* by means of cranks *K* moves the platen *T* once to and fro, the connecting rods *e* attached to toothed wheel *c* guide the roller carriages once around the middle part of 30 the press.

This arrangement can be provided for 35 both sides of the machine. But as it would require a double driving action in regard to the wheels *d*, *c*, it is advisable to attach the wheel drive to one side only and to crank the connecting rod *e* in such a manner that it extends at right angles across the middle 40 part and can guide with its second end *e'* (Fig. 2) the other parts of the carriage running in member *y*.

Drive by means of a connecting rod offers the possibility for a more roomy fastening of the middle part to the side opposite the wheel drive *c*, *d*, as there is no drive 45 on that side and no free space required for the passage of the connecting rods.

The gripper carriages *A* are guided by a cranked connecting rod like the inking roller carriages *W*. The mode of action is the same as for the drive of the roller carriages.

The rotatory motion of the grippers *m* is caused by the runner lever *p* whose roll *p'* runs in groove *q*; *s* is a toothed gearing re-

ceiving its motion from the lever *p'*. The runner lever *p* runs with its runner in a 55 deep curved groove *q* around the machine; this curved groove *q* maintains a varying distance from the track *y* *h* of the gripper carriage and causes a gradual turning of the lever *p* around its axis and simultaneously a 60 turning of the shaft *l* with grippers *m*.

I claim:—

1. Inking and sheet delivery device in platen presses with inking rollers, inking roller carriers, sheet delivery devices and gripper carriers which are guided around the middle part of the press by means of a toothed gearing, situated in the center of the press, and by means of connecting rods.

2. Inking and sheet delivery devices in 70 platen presses in which the inking rollers are placed in a separate carriage actuated by a gearing whose one wheel guiding the inking roller carriage by means of a connecting rod is placed on the hub-like side 75 part of the middle part of the press.

3. Inking and sheet delivery device in platen presses in which the connecting rod guiding the inking roller carriage is provided with an arm linked on at right angles 80 which extends over the whole width of the machine and, with its other end, serves as guide for the inking roller carriage.

4. Inking and sheet delivery devices in 85 platen presses with gripper carriers, gripping device and connecting rods which are guided by a wheel positioned in a rotating manner on the hub-like side part of the middle part of the press and guide the gripper carrier around the said middle part.

5. Inking and sheet delivery device in 90 platen presses with gripper carriers, gripper shafts and lever arms attached to both sides of the gripper shaft and carrying rolls which run in curves; and furthermore grippers which, while the gripper carriage is passing around the middle part of the press, 95 pick up the printed sheet, turn it and guide it to a delivery table.

In testimony whereof I have affixed my 100 signature in presence of two witnesses.

EDUARD GROSSE.
